Des. 203,236

Patented Dec. 14, 1965

203,236

REFRIGERATED DISPLAY CASE

Oliver H. Thompson, 716 Cherry Ave.,
Big Rapids, Mich.

Filed Aug. 27, 1964, Ser. No. 81,480

Term of patent 14 years

(Cl. D80—11)

FIG. 1.

FIG. 2.

FIG. 3.

FIG. 1 is a perspective view taken from the front and one end of a refrigerated display case showing my new design;

FIG. 2 is a rear elevational view thereof; and

FIG. 3 is an elevational view taken from the end opposite that shown in FIG. 1.

I claim:

The ornamental design for a refrigerated display case, substantially as shown and described.
